UNITED STATES PATENT OFFICE.

DAVID NICKEL AND CHARLES ZATTAN, OF MORRIS, ILLINOIS.

SPRING-HINGE.

SPECIFICATION forming part of Letters Patent No. 297,946, dated April 29, 1884.

Application filed February 4, 1884. (Model.)

To all whom it may concern:

Be it known that we, DAVID NICKEL and CHARLES ZATTAN, citizens of the United States, residing at Morris, in the county of 5 Grundy and State of Illinois, have invented certain new and useful Improvements in Spring Door-Hinges; and we do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 Figure 1 of the drawings is a front view of our hinge. Fig. 2 is a vertical sectional view. Figs. 3 and 4 are longitudinal sectional views of the same, and Figs. 5, 6, and 7 are detail views.

20 This invention has relation to double-acting spring-hinges for doors; and it consists in the construction and novel arrangement of the bearing-loops formed on the hinge-plates and the cam lugs or dogs of the shifting spring 25 centers, all as hereinafter set forth.

In the accompanying drawings, the letters 30 *a a* designate the hinge-plates, which are connected by center bearings at *b b'*, these bearings projecting from the planes of the plates, as shown. No center pin is required in the construction. The inner margin of each hinge-plate is formed with a bearing-loop, *c*, near 35 each end, adjacent to the center bearing, said bearing-loop having a rounded portion or bearing, *d*.

e represents the spring, which is an ordinary coiled-wire spring, having its terminal ends *n* and *n'* respectively turned up and down to form holding-catches.

40 Each inner bearing, *b*, is formed with a partial raised margin, *k*, on its outer or back portion, and next to the inner bearing, *b*, is arranged the outer center plate, *l*, which is pivoted to the inner center plate, *m*. The latter 45 plate is formed with an inwardly-projecting portion or bearing, *p*, for the end of the spring, a circumscribing channel or rabbet, *r*, serving to receive the end whirl of the spring, while

the projection *p* extends a short distance within the whirl, as shown.

50 The center plates, *l* and *m*, are formed with curved lugs or cam-shaped dogs *z z'*, which project in opposite directions, and engage by their inner curved edges, *s*, the bearings *d* of the loops *c*. The cam-dog *z* of the inner plate 55 is formed with a shoulder, *v*, at its heel, which is designed, when the spring is put into position, to engage its terminal catch, as shown. The cam-dog *z* of the upper and lower inner plates *l* are on opposite sides, so that the 60 ends of the spring will be held against its tension. The outer center plates, *m*, are adapted, when the hinge-plates are spread apart to their fullest extent, to move back to the marginal elevations or stops *k* of the inner bearings, *b*, of the hinge-plates. When, however, the hinge-plates are closed toward each other, the center plates *l*, and *m*, and the spring held thereby shift outward from the pivotal or axial line of the hinge-plates, this eccentric 65 position being increased as the hinge-plates are closed nearer together, until the loop-bearings of the hinge-plates are brought around forward of the axial line of the center bearings of the hinge-plates. In this position 70 the action of the spring through the cam-dogs is reversed. While before the spring, being in central position, operated to force the hinge-plates open; now the spring, being in eccentric position, operates to draw the hinge-plates 75 toward each other. In each of these movements the operation of the spring upon the hinge-plates is facilitated by the cam-dogs, which, on account of their sliding motion on the loop-bearings, render the action of the 80 hinge easy and smooth, preventing the harshness and sudden jerks which would accompany a more positive and rigid connection. The action of the spring is moderated and equalized or softened without detracting from 85 its effective force.

Having described this invention, what we claim, and desire to secure by Letters Patent, is—

1. In a double-acting spring door-hinge, the 90 inner spring center-plate, *l*, having the central

inner projection, p , to engage the end of the spring, and the shouldered cam-dog z , in combination with the outer center plate, m , also having a cam-dog, z' , and pivoted to the inner 5 plate, substantially as specified.

2. In a double-acting spring door-hinge, the combination, with the hinge-plates having raised bearings and marginal bearing-loops, of the shifting spring centers pivoted together, and having cam dogs or lugs adapted to en-

gage the bearings of the loops and slide thereon, substantially as specified.

In testimony whereof we affix our signatures in presence of two witnesses.

DAVID NICKEL.
CHARLES ZATTAN.
